UNITED STATES PATENT OFFICE

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA

COMPRESSOR-UNLOADING DEVICE

Application filed August 5, 1927. Serial No. 210,844.

This invention relates to fluid compressors, and more particularly to an unloading device for a fluid compressor.

The invention has special reference to a compressor which operates continuously, as distinguished from the type in which the compressor is stopped when the pressure of fluid compressed by the compressor has been increased to a predetermined degree and is started when the pressure of fluid has been reduced to a predetermined degree.

With a continuously operating compressor, it is necessary to provide an unloading device to relieve the compressor of its load when the pressure of fluid compressed has been increased to a predetermined degree, and the principal object of my invention is to provide an improved compressor unloading device of the above type.

In the accompanying drawing, the single figure is a sectional diagrammatic view of a compressor and an unloading device therefor and embodying my invention.

A portion 1 of a fluid compressor cylinder is shown in the drawing, having the usual compressor piston 2 and provided with an inlet valve 3 and a discharge valve 4, mounted in the cover plate 5.

The compressor discharges fluid compressed by the compressor into a tank or reservoir 6, by way of the discharge valve 4.

Disposed in the cover plate 5 is a flexible diaphragm 7, having the chamber 8 at one side connected by pipe 9 to the reservoir 6, a pressure plate 10 engaging the diaphragm 7 is disposed in the chamber 11 at the opposite side of the diaphragm.

Pivotal fulcrumed on lugs 12 carried by the diaphragm chamber cover plate 13 is a lever 14 and threaded into the short arm 15 of the lever is an adjustable screw 16 adapted to engage the outer face of a thimble 17. Interposed between the pressure plate 10 and the inner face of the thimble 17 is a ball 18 which serves to transmit movement from the diaphragm 7 to the lever 14. The ball 18 permits relative movement of the parts and prevents cocking or jamming, such as might occur with the use of the usual operating stem or member.

A coil spring 19 having one end disposed in a recess in the cover plate 5, has its opposite end in engagement with a spring follower 20, movable in a recess in the long arm 21 of the lever 14, and engaging the follower 20 is an adjustable screw 27.

Mounted in a recess in the cover plate 5 which opens to the piston chamber 23 is a relief valve 24, having an operating stem 25, which extends through a bore in the cover plate and carries at its outer end a spring follower 26. Interposed between a flange of the follower 26 and the cover plate 5 is a coil spring 27.

The outer end of the arm 21 extends downwardly and carries a roller 28, and pivotally connected between lugs 29 carried by the cover plate 5 is an arm 30. The free end of the arm 30 is provided with a lug 31 having oppositely inclined faces 32, one or the other of which is in engagement with the roller 28, according as the lever 14 is in its loaded or its unloaded position.

A coil spring 33, has one end disposed in a recess in the cover plate 5 and the other end engages in a recess in the arm 30.

The upper end of the valve stem is engageable by the head of an adjustable screw 34, which has screw-threaded engagement in the arm 21.

In operation, as the compressor operates to compress fluid into the reservoir 6 in the usual manner, the pressure in chamber 8 of the diaphragm 7 is increased. When the pressure has been increased sufficiently to overcome the opposing pressure of the spring 19, the diaphragm 7 tends to operate the lever 14, but the engagement of the roller 28 with the inclined face 32 of the arm 30 offers a momentary resistance to the movement of the lever. When the pressure in chamber 8 is sufficient to overcome this resistance, the roller 28 slips downwardly past the lug 31, so as to cause a quick, snaplike action of the lever 14. The downward movement of lever 14 then operates to cause movement of the valve stem 26 and the opening of the vent valve 24.

The opening of valve 24 connects piston chamber 23 with the atmosphere through passage 34, so that the compressor now oper-

ates without compressing fluid and therefore without load.

When the pressure in the reservoir 6 has been reduced to a predetermined degree, the 5 spring 19 tends to move the lever 14 upwardly, but this movement is momentarily resisted by the engagement of the roller 28 with the lower inclined face 32 of the arm 30. When this 10 resistance is overcome, the roller slips past the lug 31 with a quick, snaplike action, and then the upward movement of lever 14 permits the valve 24 to be closed by the action of the spring 27 through the stem 26.

Without this feature, there would be a tendency for the gradual increase in pressure on 15 the diaphragm 7 to gradually move the lever 14 and cause a partial opening of the valve 24 and thus a balanced condition might be obtained, such that the compressor would continue to operate at partial load.

Having now described my invention, what I claim as new and desire to secure by Letters Patent, is:

1. The combination with a fluid compressor, of means for unloading the compressor comprising a pressure sensitive element subject to the pressure of fluid compressed by the compressor, a lever directly operated by 25 said element, a valve directly operated by said lever for unloading the compressor, a movable arm having an inclined face engaged by said lever, and a spring for opposing movement of said arm by said lever.

2. The combination with a fluid compressor, of means for unloading the compressor comprising a pressure sensitive element subject to the pressure of fluid compressed by the compressor, a lever having one arm directly 35 movable in one direction by said element, a valve directly operated by the other arm of said lever for unloading the compressor, a pivoted arm having an inclined face engaged by a portion of said lever, and a spring for opposing movement of said arm by said lever.

3. The combination with a fluid compressor, of means for unloading the compressor comprising a pressure sensitive element subject to the pressure of fluid compressed by the compressor, a lever having one arm directly 45 movable in one direction by said element, a valve directly operated by the other arm of said lever for unloading the compressor, a pivoted arm having one inclined face engaged by a portion of said lever when the lever moves in one direction and another inclined face engaged by a portion of said lever when the lever moves in the opposite direction, and a spring for opposing movement of said arm by said lever.

4. A fluid compressor unloader comprising a fulcrumed lever, a pressure sensitive element subject to the pressure of fluid compressed and engaging said lever at one side of the fulcrum, an unloading valve having a 65 stem engaging said lever at the other side of

the fulcrum, and a spring engaging the lever between the valve stem and the fulcrum.

5. A fluid compressor unloader comprising a fulcrumed lever, a pressure sensitive element subject to the pressure of fluid compressed and engaging said lever at one side of the fulcrum, an unloading valve having a stem engaging said lever at the other side of the fulcrum, a spring engaging the lever at a point intermediate the engaging points of the valve stem and the fulcrum, and a snap action device engaging the lever at a point disposed outwardly of the point of engagement of said valve stem.

In testimony whereof I have hereunto set my hand.

CLYDE C. FARMER.
